UNITED STATES PATENT OFFICE

WILLIARD M. McBRIDE, OF PITTSBURGH, PENNSYLVANIA

REAMER

Application filed July 2, 1927. Serial No. 203,137.

This invention relates to boring tools and more particularly to such as are designed to enlarge openings for truing, or to receive oversize or larger parts.

5 The invention provides a reamer which is adjustable in diameter within certain limits and which is free from external projecting parts and rigid and durable, the blades being readily removable for replacement and firmly 10 secured to the required adjusted position against possible displacement.

While the drawings illustrate a preferred embodiment of the invention, it is to be understood that in adapting the means to meet 15 specific needs and requirements, the design may be varied and changes in the minor details of construction may be resorted to within the scope of the invention as claimed, without departing from the spirit thereof.

20 For a full understanding of the invention and the merits thereof, reference is to be had to the following description and the drawings hereto attached, in which,—

25 Figure 1 is a side view of a reamer, embodying the invention.

Figure 2 is a central, longitudinal, sectional view of the reamer, the adjusting bar being in full lines.

30 Figure 3 is a view similar to Figure 1, the blades being omitted.

Figure 4 is a detail perspective view of an end portion of the adjusting bar.

35 Figure 5 is a detail sectional view on the line 5—5 of Figure 1.

Figure 6 is a detail sectional view on the line 6—6 of Figure 1.

Corresponding and like parts are referred to in the following description and designated in the several views of the drawings by like reference characters.

40 The body of the reamer is designated by the numeral 1, and may be of any length and diameter depending upon the size of the tool. An opening 2 is formed axially of the body and extends therein a distance from one end depending upon the length of the tool, and the cutting blades. Longitudinal slots 3 are formed in the sides of the body 1 and open outwardly from the axial bore 2. These slots 45 are disposed equidistantly about the sides of

the body and are of a uniform width and have a radial arrangement. The parts 4 separated by the slots 3 are bracingly connected by bridge portions 5 and 6, which form a part of the body 1, the connecting portion 6 being at 55 the outer end of the body and the connecting portion 5 intermediate the ends of the parts 4. The length and the number of the slots 3 will depend upon the size and particular work for which the tool is designed. 60

A blade 7 is provided for each of the slots 3 and is of a size to snugly fit the slots. The back portion of each of the blades 7 is notched to receive the connecting portions 5 and 6, as shown in Fig. 2. The outer or cutting portion of the blade is reduced, as indicated most clearly in Figure 5. The back of the blade is made rounding, as indicated most clearly in Figure 5, so as to offer a minimum resistance to and facilitate the action of the adjusting 70 bar. Screws 8 threaded into openings formed in the parts 4 serve as means to secure the blades 7 in the required adjusted position. The heads of the screws 8 are of conical formation and are adapted to engage correspondingly notched portions of the blades, as will be understood on reference to Fig. 5. While the drawings show two screws 8 for each of the blades 7, it is to be understood that the number of screws to each of the 80 blades will depend upon the length of the blades and the size of the tool. 75

An adjusting bar 9 snugly fits within the axial opening or bore 2, and its end portions 10 and 11 are of circular formation corresponding to the diameter of the opening 2, whereas the intermediate portion is of polygonal formation, the flat sides 11^a corresponding in number to the number of the slots 3, so that a flat side 11^a is had for each of the blades 90

7. As shown most clearly in Figure 5 of the drawings, the body 1 is formed with six slots 3, hence the polygonal portion of the bar 9 is of hexagonal outline. When the parts are assembled a flat side 11^a of the adjusting bar comes opposite a slot 3, and the inner end or back of the blade 7 engages a flat side of the bar so that rotation of the bar, either to the right or to the left, will effect an outward movement of the blades, thereby increasing the 100

diameter of the tool. Rotation of the adjusting bar 9 is effected by cutting away portions 12 from opposite sides of the end 10, whereby to form a reduced portion 13 having opposite flat sides against which the inner ends of screws 14 engage, said screws being threaded into openings formed in opposite sides of the body 1. When both screws 14 engage opposite sides of the reduced portion 13 the adjusting bar 9 is held in fixed position and by backing one of the screws 14 and advancing the other screw, the adjusting bar will be turned to cause the flat sides 11^a to ride upon the inner ends or backs of the blades 7 and move said blades outwardly. Preliminary to outward adjustment of the blades 7 the fastening screws 8 are backed a distance to admit of the outward movement of the blades. After the blades have been adjusted they are made secure by retightening the screws 8, as will be readily understood.

The tool is free from outwardly projecting parts, and the portions 4 separated by the slots 3 are bracingly connected by the portions 5 and 6, and in consequence, the tool possesses the rigidity of a solid reamer, with the advantages of being adjustable and provided with replaceable and removable blades. Displacement of the adjusting bar is prevented by means of the screws 14 entering the cutaway portions 12.

Adjacent flat sides 11^a of the adjusting bar 9 do not intersect and form angles, but are connected by small arcuate portions 11^b which obtain a bearing against the inner wall of the bore 2 and thus support the bar 9 at points between each two adjacent flat sides 11^a.

The invention provides an adjustable inserted blade reamer embodying features which may be incorporated in analogous tools containing cutter elements which are adjustable by means of a rotary member.

By the use of these new improvements a positive accurate adjustment can be made to expand and contract the outside diameter of the inserted blades. Many advantages are attained by the use of the special rotary adjusting features herein set forth, which are as follows:

It is not bulky or cumbersome in any way. There are no obstructions on the outside of this reamer to hinder full and complete use of this tool to the same extent that a solid tool could be used. It is very rigid due to the reinforced bridges across the slots. The rigidity of this tool is further increased due to the adjusting bar 9 fitting neatly in the hole in the body or shell of the tool. Also the bar adjusting screws 14 serve as lock screws as well as for making the bar rotate when adjusting. This feature of locking the bar firmly makes a large degree of accuracy possible.

Having thus described the invention I claim:

A reamer comprising an elongated body having an axial opening and a plurality of longitudinal slots and further provided with aligned transverse threaded openings inwardly from the slots leading into opposite sides of the axial opening, blades in the slots, a bar having end portions of cylindrical formation and its intermediate portion polygonal, one end portion fitting within the axial opening of the body and having portions cut from its opposite sides to define transversely aligned recesses and a central radial web, said recesses being aligned with the transverse openings in the body and the polygonal portion of the bar bearing against the inner edges of the blades, and screws threaded into the transverse openings in the body and housed therein with their inner ends engaged in the recesses in the bar and bearing against opposite sides of the web to retain the bar in place and effect its rotation for adjusting the blades.

In testimony whereof I affix my signature.

WILLIARD M. McBRIDE. [L. s.]
